(57) **CLAIM**

The ornamental design for a pair of non-slip ventilated socks, as shown and described.

DESCRIPTION

FIG. 1 is a top perspective view of a pair of non-slip ventilated socks showing my new design

FIG. 2 shows a top plan view thereof;

FIG. 3 shows a bottom plan view thereof;

FIG. 4 shows a right side elevational view of the right sock of FIG. 2;

FIG. 5 shows a left side elevational view of the left sock of FIG. 2;

FIG. 6 shows a left side elevational view of the right sock of FIG. 2;

FIG. 7 shows a right side elevational view of the left sock of FIG. 2;

FIG. 8 shows a front elevational view of the pair of FIG. 1; and,

FIG. 9 shows a rear elevational view thereof.

The flat circular details shown in FIG. 3 represent a change of material.

The broken lines shown in the drawing views are for purposes of illustrating portions of the pair of non-slip ventilated socks that form no part of the claimed design.
